US00D770365S

(12) **United States Design Patent** (10) **Patent No.:** **US D770,365 S**
(45) **Date of Patent:** **** Nov. 1, 2016**

(54) **TIRE**

(71) Applicant: **Zhenjiang Yu**, Tianjin (CN)

(72) Inventor: **Zhenjiang Yu**, Tianjin (CN)

(73) Assignee: **Tianjin Wanda Tyre Group Co., Ltd.**
(CN)

(**) Term: **15 Years**

(21) Appl. No.: **29/542,414**

(22) Filed: **Oct. 14, 2015**

(51) LOC (10) Cl. **12-15**

(52) U.S. Cl.

USPC **D12/544**

(58) **Field of Classification Search**

USPC **D12/500-579; 152/209.12**

CPC **B60C 11/0306; B60C 11/11; B60C 11/0318; B60C 2200/14**

See application file for complete search history.
